SAFETY GUARD CATCH FOR ELEVATOR ENTRANCES

Filed Oct. 2, 1929

INVENTOR.
Carl Henningsen
BY *Otto R. Polachek*
ATTORNEY

UNITED STATES PATENT OFFICE

CARL HERMSEN, OF ASTORIA, NEW YORK

SAFETY GUARD CATCH FOR ELEVATOR ENTRANCES

Application filed October 2, 1929. Serial No. 396,659.

This invention relates to new and useful improvements in holding means for gates.

The invention has for an object the provision of a device of the class mentioned which is of simple durable construction, dependable in use and efficient in action, and which can be manufactured and sold at a reasonable cost.

The holding means for gates is intended for application upon the top of a gate at the ends thereof and it is proposed to construct each holding means with a bracket for attachment upon the top of the gate and formed with a passage, rods extending thru the passage and formed with end fingers, and means for holding the rods in various fixed positions.

A gate provided with holding means according to this invention may be easily engaged in place in a door frame or window frame. Further it is adjustable to fit any sized thickness of frame and no special brackets are required upon the frame for coaction with the holding means. When in applied position, there is no danger of it becoming disengaged and the gate with possible persons leaning against it become exposed to dangers.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is an elevational view of a door in a wall and a gate provided with the holding means applied in the door frame.

Fig. 2 is an enlarged fragmentary horizontal sectional view taken on the line 2-2 of Fig. 1.

Fig. 3 is a vertical sectional view of the holding means per se, taken on the line 3-3 of Fig. 2, the fingers of the holding means being shown turned downwards.

Fig. 4 is an enlarged plan view of the holding means shown in Fig. 2.

Fig. 5 is a fragmentary sectional view taken on the line 5-5 of Fig. 3.

Fig. 6 is a view similar to Fig. 5 but illustrating a modified form.

Fig. 7 is a fragmentary view of a portion 55 of Fig. 3 illustrating another embodiment of the device.

The holding means for gates is intended for application upon the top of a gate at the ends thereof and each holding means consists of a bracket 10 for attachment upon the top of the gate and formed with a passage 11, rods 12 extending thru the passage and formed with end fingers 13, and means 18 for holding the rods in various fixed positions. 65

In Fig. 1 numeral 14 indicates a wall provided with a door opening 15 and a door 16. This door may communicate with an elevator shaft, or the like. During the nighttime it is customary to close such doors but during the daytime they are left open. While in an open position, it is necessary to guard against persons accidentally walking thru and falling down the elevator shaft or other similar occurrence. For this reason a gate 70 17 is inserted across the frame of the door when the door is in its open position. This gate may be of conventional construction. It is provided with a holding means 18 on each end and on the top thereof. These 75 holding means serve to maintain the gate in position and permit easy removal thereof during the construction of a building.

The said bracket 10 of the holding means 80 consists of a base plate 19 formed with apertures 20 for the passage of screws for the attachment upon the top of the gate. An inverted U shaped member 21 is positioned upon the said plate 19 and provides the said 85 passage 11. This member 21 is formed with bottom lugs 22 extended thru apertures in the plate 19 and then riveted over for maintaining its position. It is also provided with a boss 23 at its top.

The said rods 12 are formed with serrated 90 portions 24 or portions roughened in any other manner. These rods are arranged one above the other as may be clearly seen from an inspection of Fig. 5. A portion of the plate 19 is roughened where the lower rod 12 95 100

contacts therewith. This roughened portion is indicated by reference numeral 25.

The said fingers 13 are integral with the rods 12 and are directed at right angles thereto. They are substantially parallel to each other and when engaged upon a door frame are positioned on opposite sides thereof. The said means for holding the rods in various fixed positions consists of a button 26 arranged between the top rod 12 and the bottom of the bend of the U shaped member 21. The top surface 27 on the button is inclined as shown in Figs. 3. The bottom surface of the boss 23 is provided with a similar incline 28. An arbor 29 is fixed on the top of the button and extends thru the boss 23. A handle 30 is attached upon the free end of the arbor 29.

In the modified form of the device illustrated in Fig. 6, a U member 21' has been illustrated formed of two sections, namely an upper section 31 and a lower section 32. Lugs 33 project from these sections and screws 34 threadedly engage the lugs. These screws have lower right hand threaded portions for engaging the lugs of the section 32 and upper left hand portions for engaging the lugs of sections 31. Upon rotation of the screws, the sections 31 and 32 may be moved closer together or further apart for adjusting the relation between the inclined surfaces 27 and 28. This adjustment is extremely advantageous when the button 26 becomes worn after some use.

In the modified form illustrated in Fig. 7, means for holding the rods in various fixed positions have been illustrated and consists of a lever 35 pivotally mounted at 36 upon the bracket 10 and formed with a cam portion 37 engageable firmly against the top rod 12, when in a lower position. When pivoted upwards as indicated by dot and dash lines 38, the cam surface is disengaged from the rods.

In operation of the various holding means for gates, particularly when in position upon a gate, the means for holding the rods in various fixed positions is loosened so that the rods 12 are free for extension and for rotation. The fingers 13 of the rods are placed on opposite sides of the door frame or window frame as the case may be and then the holding means for the rods is reengaged for locking them in the latter mentioned position. Thus the gate is firmly held in place.

The roughened surfaces 24 prevent any possible disengaging of the rods when the means for holding the rods is in operative condition. For disengaging the gate, it is merely necessary to disengage the means for holding the rods and then move the fingers 13 downwards to a position shown in Fig. 3.

While I have shown and described the preferred embodiment of my invention, it is to be understood that I do not limit myself

to the precise construction herein disclosed and the right is reserved to all changes and modifications coming within the scope of the invention as defined in the appended claims.

Having thus described my invention, what I claim as new, and desire to secure by United States Letters Patent is:

1. In combination with a gate, a holding means, comprising a bracket for attachment on the top of the gate and formed with a passage, rods extending thru the passage and formed with end fingers for engaging the opposite sides of a door or window frame, and means for holding the rods in various fixed positions.

2. In combination with a gate, a holding means, comprising a bracket for attachment on the top of the gate and formed with a passage, rods extending thru the passage and formed with end fingers for engaging the opposite sides of a door or window frame, and means for holding the rods in various fixed positions, said bracket consisting of a base plate and an inverted U shaped member secured thereon and providing the said passage.

3. In combination with a gate, a holding means, comprising a bracket for attachment on the top of the gate and formed with a passage, rods extending thru the passage and formed with end fingers for engaging the opposite sides of a door or window frame, and means for holding the rods in various fixed positions, said rods being formed with serrated or roughened portions for supplementing the means for holding the rods.

4. In combination with a gate, a holding means, comprising a bracket for attachment on the top of the gate and formed with a passage, rods extending thru the passage and formed with end fingers for engaging the opposite sides of a door or window frame, and means for holding the rods in various fixed positions, said rods being one above the other for the purpose described.

5. In combination with a gate, a holding means, comprising a bracket for attachment on the top of the gate and formed with a passage, rods extending thru the passage and formed with end fingers for engaging the opposite sides of a door or window frame, and means for holding the rods in various fixed positions, said fingers being integral with the rods and at right angles thereto and parallel with each other.

6. In combination with a gate, a holding means, comprising a bracket for attachment on the top of the gate and formed with a passage, rods extending thru the passage and formed with end fingers for engaging the opposite sides of a door or window frame, and means for holding the rods in various fixed positions, comprising a button engageable against one of said rods for urging the rods together and against the bracket, man-

ual means for rotating the button, and an inclined surface on the bracket for engaging against an inclined surface on the button during rotation of the latter element for engaging said rod.

5 7. In combination with a gate, a holding means, comprising a bracket for attachment on the top of the gate and formed with a passage, rods extending thru the passage and formed with end fingers for engaging the opposite sides of a door or window frame, and means for holding the rods in various fixed positions, comprising a button engageable against one of said rods for urging the 10 rods together and against the bracket, manual means for rotating the button, and an inclined surface on the bracket for engaging against an inclined surface on the button during rotation of the latter element for engaging 15 said rod, said bracket being of two sections adjustably connected for adjustments of the inclined surfaces relative to 20 each other.

25 8. In combination with a gate, a holding means, comprising a bracket for attachment on the top of the gate and formed with a passage, rods extending thru the passage and formed with end fingers for engaging the opposite sides of a door or window frame, and means for holding the rods in various fixed 30 positions, comprising a lever pivotally mounted on the bracket and formed with a cam portion engageable against one of said rods for urging the rods together and against the bracket, in a lowered position.

25 In testimony whereof I have affixed my signature.

CARL HERMANSEN.
